UNITED STATES PATENT OFFICE

CARL BÜCHNER, OF MANHEIM-WALDHOF, GERMANY, ASSIGNOR TO PAPYRUS A. G.,
OF MANNHEIM-WALDHOF, GERMANY

PAPER MAKING MACHINE

Application filed January 17, 1929, Serial No. 333,091, and in Germany February 14, 1928.

As is well known, it is of great importance to keep under observation and to regulate the degree of fineness to which the pulp fed to paper making machines is ground.

5 According to the present invention this degree of grinding can be observed continuously at the paper making machine directly and may be automatically regulated.

The invention consists in this, that a 10 greater or less portion of the water which runs down through the sieve of the paper making machine is continuously measured and that any fluctuations in the quantities are utilized for initiating regulating operations.

15 Usually the water running down through the sieve is caught in a plurality of troughs lying one beyond the other and is conveyed away to the side to be used again. When a uniform quantity of water flows to the sieve 20 per unit of time, the degree of grinding of the pulp however varying, both the total quantity of the water flowing down and the part quantities apportioned to the separate troughs alters. The greatest fluctuations occur 25 mostly in the first trough immediately behind the breast roll. The coarser the pulp, in other words the less the degree of communication, the more water will escape at this point.

In the next sieve sections there will also be 30 fluctuations in the quantity, but these will also be influenced by the fact that the first sieve section has already let through more water, so that less water remains to be passed on.

The new method consists in measuring 35 continuously the quantity of water which flows down on the whole sieve or at one part of the sieve found to be particularly suitable for the purpose by means of any known device. This may, for instance, be effected by providing 40 at the outflow of the particular water trough a measuring box having a constant outflow opening, a so-called danaide, the water level of which is observed by means of a float and a pointer.

45 In the case, for example, of the first trough behind the breast roll the float will stand higher with coarse pulp and lower with smearable pulp, so that the machine attendant can immediately see which way the downwardly flowing pulp deviates from the de-

sired medium degree of grinding. It is then easy to take the necessary steps for making a uniform paper. In cases in which, owing to the provision of a conical pulp grinding mill, it is possible rapidly to influence the 55 degree of grinding, according to the invention a further step can be taken and the quantity of water passing through the sieve may be utilized for automatically regulating the degree of grinding. This may for instance 60 be effected by providing electric limiting contacts on the float of the measuring box, the contact of which causes an electric regulating motor to adjust the spindle of the conical pulp mill so as to be tighter or looser. Mechanical or hydraulic servo motors or the like may of course also be used, or the grinding apparatus may be influenced indirectly. 65

In the accompanying drawings a constructional example of the invention is shown. 70 Fig. 1 shows a part rear end view of a paper making machine of the Fourdrinier type showing the measuring box according to the invention in section. Fig. 2 is a part plan view of the arrangement shown in Fig. 1. Fig. 3 shows in elevation a portion of the rear end of the paper making machine, partly in section. 75

Referring to the drawings, *g* is the breast roll, over which passes the sieve wire *i*, *h* are the deckle-straps which rest on the edges of the sieve wire and *l* the table rolls of the machine. The pulp is fed to the breast roll from a pulp or stock box (not shown) and the water which flows from the pulp through the sieve *i*, which is supported by and moved by the breast roll *g* and the table roll *i*, passes between the rolls *i* into the sieve water troughs *f*. The water in the sieve water 80 troughs *f* flows into a measuring trough *a* in which is a float *b*. This measuring box is preferably arranged below the first sieve water trough *f* directly following the breast roll *g*, but it can be arranged at any other 85 suitable point along the sieve *i* suitable for the removal of the sieve water.

The differences in level of the water in the measuring box *a* corresponding to variations 90 in the delivery of the sieve water thereto are 95 100

measured by a liquid level indicating device of any suitable kind *m*. In Figure 1, the indicating device *m* is shown conventionally as a pointer fixed to a pulley over which passes a flexible member attached to the float, the movements of the latter causing the pointer to move over a graduated scale. In the measuring box *a* baffles *c* and *d* are provided, the object of which is to calm the sieve water, in order that the float *b* will not be caused to swing to and fro. By adjusting the cross-sectional area at the outflow *e* in the bottom of the box, the sieve water in the box is kept at a definite level. Means are also provided for connecting the float *b* to means for regulating the action of a conical pulp mill, for influencing the latter as required by the quality of the paper pulp to be produced. In Figure 1, a regulating device is shown comprising a switch *n* having a plurality of contacts *k* which are for instance connected up to the circuit of a regulating motor which controls the grinding pressure of a conical pulp mill by varying the setting of the conical rollers with respect to the roller casing. Should, for instance, during a working operation too much sieve water enter the troughs *f* or the box *a*, that is should the pulp be too little or too coarsely ground, the float *b* will rise and will influence the conical mill and consequently the degree of grinding of the pulp in such a manner that the normal quantity of sieve water will again pass into the sieve water trough *f* or the box *a*. When there is a smaller outflow of sieve water, the float *b* will actuate the conical pulp mill in the opposite sense.

What I claim is:

1. A method of checking and regulating the degree of grinding of the pulp supplied to paper making machines having a sieve, consisting in measuring the quantity of flow of at least a portion of the water flowing down through the sieve of the paper making machine, observing fluctuations in the said quantity of flow and adjusting the grinding of the pulp to restore the quantity of flow to the normal value, as and for the purpose set forth.

2. The combination with a paper making machine having a sieve for separating the water from the pulp, means for leading away the water flowing down through the sieve and a grinding mill having means for regulating the degree of grinding, of a measuring apparatus having indicating means for measuring the quantity of flow of at least a portion of the water flowing away from the sieve and actuating means connected to said indicating means for operating the means for regulating the degree of grinding, as and for the purposes set forth.

3. A method of checking the degree of grinding of the pulp supplied to paper mak-

ing machines having a sieve, consisting in utilizing the flow of at least a portion of the water flowing down through the sieve and varying in quantity according to the degree of grinding of the paper machine for indicating the degree of fineness of the grinding.

4. A method of checking the degree of grinding of the pulp supplied to paper making machines having a sieve, consisting in utilizing the flow of at least a portion of the water flowing down through the sieve and varying in quantity according to the degree of grinding of the paper machine for indicating and regulating the degree of fineness of the grinding.

5. In combination, a paper making machine having a sieve for separating the water from the pulp, a trough for leading away the water flowing down through the sieve, and a measuring apparatus, said apparatus including a receptacle arranged to receive at least a portion of the water flowing in the trough, outflow means for controlling the outflow of water from the receptacle to maintain the water level at a substantially constant value during normal operation of the machine, and a measuring float in said receptacle.

In testimony whereof I have signed my name to this specification.

CERTIFICATE OF CORRECTION.

Patent No. 1,876,563.

September 13, 1932.

CARL BÜCHNER.

It is hereby certified that the above numbered patent was erroneously issued to "Papyrus A. G.", as assignee of the entire interest in said invention, whereas said patent should have been issued to the inventor said "Büchner" and the "Papyrus A. G." as assignee of one-half interest only as shown by the records of assignments in this office; and that the said Letters Patent should be read with this correction therein that the same may conform to the record of the case in the Patent Office.

Signed and sealed this 24th day of January, A. D. 1933.

**M. J. Moore,
Acting Commissioner of Patents.**
